UNITED STATES PATENT OFFICE

119,657

DESIGN FOR AN ASH RECEPTACLE OR SIMILAR ARTICLE

James Carl Hinkle, Huntington Park, Calif.

Application May 26, 1939, Serial No. 85,223

Term of patent 7 years

To all whom it may concern:

Be it known that James Carl Hinkle, a citizen of the United States, residing at Huntington Park, in the county of Los Angeles and State of California, has invented a new, original, and ornamental Design for an Ash Receptacle or Similar Article, of which the following is a specification, reference being had to the accompanying drawing, forming part thereof.

Fig. 1 is a front elevational view of the ash receptacle showing my new design;

Fig. 2 is a side elevational view; and

Fig. 3 is a top plan view thereof.

I claim:

The ornamental design for an ash receptacle or similar article, as shown.

JAMES CARL HINKLE.
